(57) **CLAIM**

The ornamental design for a camp fire cooking rack, as shown and described.

DESCRIPTION

FIG. 1 is a perspective view of a camp fire cooking rack showing my new design fully assembled;

FIG. 2 is a side view of the top portion of the support shown in FIG. 1;

FIG. 3 is a rear view of FIG. 2;

FIG. 4 is a front view of FIG. 2;

FIG. 5 is a top view of FIG. 2;

FIG. 6 is a bottom view of FIG. 2;

FIG. 7 is a side view of the cooking rack portion shown in FIG. 1;

FIG. 8 is a rear view of FIG. 7;

FIG. 9 is a front view of FIG. 7;

FIG. 10 is a top view of FIG. 7;

FIG. 11 is a bottom view of FIG. 7;

FIG. 12 is a side view of the ground engaging portion shown in FIG. 1;

FIG. 13 is a rear view of FIG. 12;

FIG. 14 is a front view of FIG. 12;

FIG. 15 is a top view of FIG. 12;

FIG. 16 is a bottom view of FIG. 12;

FIG. 17 is a side view of the central pole portion shown in FIG. 1; and,

FIG. 18 is a top view of FIG. 17.

The parts are shown separate for clarity of illustration. The claim is directed to the fully assembled article shown in FIG. 1.
